UNITED STATES PATENT OFFICE

1,982,891

MACHINE FOR MOLDING FLOOR SLABS

Frederick M. Venzie, Philadelphia, Pa.

Application November 18, 1931, Serial No. 575,837

3 Claims. (Cl. 25—41)

This invention relates to apparatus for the molding of floor slabs as used in building constructions, as for example the floor slab shown in my Patent No. 1,891,513.

- 5 One object of the present invention is to provide a simple, compact, and efficient machine which may be conveniently handled by the operator to form upon the under face of a floor slab a plurality of pendant flanges.
- 10 A further object of the present invention is to provide a machine of this character in which the depth of the pendant flanges may be readily varied by suitable adjustments upon the machine.
- A further object of the present invention is to provide a machine of the character stated provided with a vertically movable table co-operative with a plurality of fixed ribs, whereby variations may be secured in the depth of the pendant flanges upon the floor slabs.
- 20 A further object of the present invention is to provide a machine of the character stated in which there is provided a removable frame above said movable table for co-operating with the table parts in the molding of floor slabs.
- 25 A still further object is to provide a machine of the character stated in which slabs may be cast both the length and the height of which may be predetermined to meet existing conditions in building structures.
- 30 A still further object of the present invention is to provide a machine of the character stated in which provision is made both for the molding of slabs as to different lengths and different heights.

35 Other and further objects of the present invention reside in the provision of general details of construction and in the arrangement, combination, and connection of parts for attaining the results sought by the foregoing objects.

40 The invention consists of the novel construction hereinafter described and finally claimed. The nature, characteristic features and scope of the invention will be more fully understood from the following description taken in connection with the accompanying drawings forming part hereof, and in which:

Fig. 1 is a top or plan view of a machine embodying the invention, with the removable frame omitted;

Fig. 2 is a view in side elevation of the machine illustrated in Fig. 1 with the removable frame in operative position;

Fig. 3 is a view in section taken upon the line 55 3—3 of Fig. 1;

Fig. 4 is a view in section taken upon the line 4—4 of Fig. 3;

Fig. 5 is a fragmentary view in plan of the removable frame shown in Figs. 2 and 3;

Fig. 6 is an end view of the construction shown in Fig. 5;

Fig. 7 is an end view of one of the floor slabs;

Fig. 8 is a view in side elevation of the slabs shown in Fig. 7.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring now to the drawings in detail, the reference numeral 10 designates a pair of end standards which support at their tops a horizontally disposed frame 11. Journalled in the end standards 10 as at 12 are a pair of horizontally arranged shafts 13. The reference numeral 14 designates a pair of intermediate standards. These standards 14 support the intermediate portions of the shafts 13 by means of bearings 15. Fixed to each of the shafts 13 is a worm gear wheel 16, best seen in Fig. 4. These worm gear wheels 16 mesh with worm gears 17 arranged upon cross shaft 18. This cross shaft 18 is provided with a pair of hand wheels 19 whereby the shafts 13 may be operated. The function of the shafts 13 is that of elevating and lowering a table 20, best seen in Figs. 3 and 4. This table is provided with pendant rack bars 21 of which there are six, two at each end of the table and two arranged intermediate of the end rack bars. This is to provide stability in the uniform upward movement of the table. Each rack bar 21 meshes with pinions 22 upon each of the horizontal shafts 13. Thus, as the hand wheels are moved in the proper direction, motion is transmitted through worm gears 17 and worm gear wheels 16 to drive shafts 13 for elevating or lowering the table 20.

Fixed upon the top of the table 20 are a plurality of spaced longitudinally arranged rails 23 of rectangular cross-section. In practice the rails are made of tubing in order to lighten the structure. These rails 23 are arranged, in the upward movement of the table, to pass between spaced fixed rails 24 carried by the end standards 10. These rails 24 are also of rectangular cross-

section and are preferably made of tubing. Removably mounted above the rails 23 and 24 is a frame made up of side pieces 25 which in practice are designed to rest upon the upper surfaces 5 of the outermost rails 24 and have detachable connection with the end standards 12 by means of latches 26. The side rails 25 are apertured as at 27, see Figs. 3 and 5. Arranged to detachably fit between the side rails 25 are end pieces 10 28. Each end piece is provided with a laterally extended pin 29 for engaging a selective aperture 27 of a side rail 25. This construction constitutes what may be termed a dowel-pin construction. The inner face of each end piece 28 15 is slotted as at 30 to accommodate the end of reinforcing rods 31 as employed in a floor slab 32, as shown in Figs. 7 and 8. This particular form of slab and reinforcing rod is shown in my aforesaid Letters Patent. In order to support the ends 20 of the reinforcing rods 31 during a molding period, use is made of lugs 33, see Fig. 6, formed integral with the end members 28. The bottom of each end member 28 is provided with a rail 34 having detachable connection with the upper portions 25 of the members 28 so that if desired these rails 34 may be detached and others substituted in case different heights of ribs 35 are desired for the floor slabs 32.

A description will now be given of the mode of 30 operating the above described apparatus. Primarily, the table 20 with its spaced rails is adjustable to give the proper depth of space between the immovable rails 24 in order that the ribs 35 of desired height may be secured for the floor 35 slabs 32. This having been done, the end members 22 are positioned upon the tops of the immovable rails 24, and the side rails 25 of the frame used in molding the floor slabs are fitted to place so that a dowel-pin connection is obtained. The 40 latches 26 are then turned to place, thus interlocking the molding frame with respect to the upper part of the machine, as is clearly shown in Fig. 4. The reinforcing rods 31 are then caused to engage within the spaces between the immovable rails 24 and the rail tables 23, as is best seen in Fig. 4. At this time a cementitious fill is introduced with respect to the molding frame and the same permitted to set, whereupon the latches 26 are released and the side rails 25 and end members 28 removed from the top of the machine and the floor slab removed.

Among the advantages to be claimed for the above described apparatus, mention may be made

of the fact that the operator has access to both sides of the machine in using the hand wheels 19 and that very slight adjustments as to depth of spaces between the table rails and the immovable rails may be obtained both by reason of the vertically adjustable table and the replaceable rails 34 of the end members 28. 80

A further advantage resides in the fact that the molding frame may be easily set up and taken down, thus expediting time taken in a molding period. The parts are simple, inexpensive to manufacture, and reliable in operation; and very little if any effort is required to adjust and manipulate the said parts. 85

A further advantage is to take care of varied 90 lengths and heights of slabs in a molding process.

What is claimed is:—

1. A machine for forming a block from plastic material comprising a stationary table, said table being provided with longitudinal parallel slots 95 in the bottom thereof, and means, removably positioned in said slots, the side walls of said slots lying in planes normal to the plane of said table, in contact with the sides thereof, for forming portions of one face of said block, said table forming means for forming the remaining portions of said face and means for positioning said removably positioned means a predetermined variable distance below the plane of the upper face of said table, whereby grooves of predetermined variable depths may be formed in said face of said block. 100

2. A machine for forming blocks from plastic material comprising a stationary table, longitudinal parallel slots in said table, means passing 110 through said slots and co-operating with said table to form one face of a block, means detachably connected to said table for forming sides of said block, and means detachably connected to said last named means at predetermined positions intermediate their ends for forming ends on said block. 115

3. A machine for forming blocks from plastic material comprising a stationary table, longitudinal parallel slots in said table, means passing 120 through said slots and co-operating with said table to form one face of a block, means detachably connected to said table for forming sides of said block, and means connected to said sides at a position intermediate the ends of the slots in 125 said table for forming ends on said block. 130
